UNITED STATES PATENT OFFICE.

GILBERT L. CROWELL, JR., OF ARLINGTON, NEW JERSEY, ASSIGNOR TO
DOMINICK & HAEF, OF NEW YORK, N. Y.

DESIGN FOR A HANDLE FOR SPOONS, &c.

SPECIFICATION forming part of Design No. 25,019, dated December 31, 1895.

Application filed October 5, 1895. Serial No. 564,812. Term of patent 14 years.

To all whom it may concern:

Be it known that I, GILBERT L. CROWELL, Jr., a citizen of the United States, residing at Arlington, in the county of Hudson and State of New Jersey, have invented and produced a new and original Design for Handles or Spoons, Forks, and Similar Articles, of which the following is a description, reference being had to the accompanying drawings, which illustrate the design.

Figure 1 of the drawings shows in elevation the front or obverse side of a spoon-handle embodying my design, the dotted lines illustrating the application of such a handle to a fork. Fig. 2 shows the rear or reverse side of the same.

The general outline of the handle is of the pandurate or fiddle-shaped order. Both the front and rear faces of the spoon-handle are ornamented with the representation of a vine A running substantially parallel with the edge thereof and bearing clusters of leaves and grapes. The front of the handle bears at the head thereof the representation of a cluster of vine-leaves and grapes B, and a similar cluster C is located near the middle of the handle. At the junction of the shank of the handle with the bowl of the spoon or the prongs of a fork, as the case may be, there is represented another bunch of grapes and leaves D. On the reverse side the shank of the handle and the back side of the bowl of

the spoon bear the ornamentation E, consisting of intertwined vine-leaves, bunches of grapes, and tendrils, and at the head and middle of the spoon-handle are the leaf designs F and G.

The essential features of the design, as to the obverse face of the handle, consist of the pandurate outline shape of the handle and of the ornamentation of the vine border and the specific designs at the head and near the middle of the handle. The essential features of the design of the reverse face of the handle consist of the pandurate outline shape of the handle, the vine border shown on the same, and the specific designs at the head, at the near middle of the same, and at the shank end thereof.

What is claimed as new is—

1. In the design for the handle of a spoon, fork or similar article, the obverse side of the handle, substantially as shown and described.
2. In the design for the handle of a spoon, fork or similar article, the reverse side of the handle, substantially as shown and described.
3. The design for the handle of a spoon, fork or similar article, substantially as shown and described.

GILBERT L. CROWELL, JR.
